PAGE 2

FIG. 3

FIG. 4

FIGURE 1 is a top plan view of one form of a combined sink and work center, showing my new design;

FIG. 2 is a front elevational view of the embodiment shown in FIG. 1;

FIG. 3 is a top plan view of a modified form of the combined sink and work center shown in FIGS. 1 and 2;

FIG. 4 is a front elevational view of the embodiment shown in FIG. 3;

FIG. 5 is a top plan view of another modified form of the combined sink and work center shown in FIGS. 1 and 2; and

FIG. 6 is a front elevational view of the embodiment shown in FIG. 5.

The dominant features of the design reside in the full-line portions of the drawings.

This application is a continuation of my copending applications, Serial Nos. D. 58,235, D. 58,236 and D. 58,237, filed November 6, 1959, now abandoned.

I claim:

The ornamental design for a combined sink and work center, substantially as shown and described.
